UNITED STATES PATENT OFFICE

MEAD HEDGLON, OF SYRACUSE, NEW YORK, ASSIGNOR TO M. L. OBERDORFER BRASS COMPANY, OF SYRACUSE, NEW YORK, A CORPORATION OF NEW YORK

GEARED PUMP

Application filed April 7, 1930. Serial No. 442,288.

This invention relates particularly to marine pumps, of the rotary type, designed for lifting and effecting the circulation of water, oils and other liquids, and has for its object to provide simple means to replace, from time to time, certain of the worn out parts of the pump, without necessitating the discarding of the driving and related parts.

Heretofore, when the bearing surfaces of the gears and housing of a pump proper become worn away and useless, due to sand and other gritty sediment being carried into the pump when the waters of the sea or other source become roiled or turbid, it has been more or less the common practice to throw away, not only the movable pump parts, including the gears and housing, but also to discard the whole of the pump mechanism and replace the same with a new pump. This not only occasions the stoppage of the pumping work for a considerable time, but also involves considerable extra expense and the loss of many useful parts. The present invention has for its primary object to modify the body and housing structure in such manner as to enable the operator to readily and quickly remove the gears and housing that have become worn out and to replace said parts by new ones without disturbing the body or the driving parts. A further object is to provide a cheek-piece or bush-lining of bronze or other suitable metal, which may be interposed between the housing and the main body, in direct contact with the inner ends of the pump gears, to the end that the wear effected by the pump gears, which ordinarily erodes and distorts the adjacent face of the body, may be absorbed entirely by the cheek-piece, and thus leave the body uninjured. In practice, the opposing plane faces of the cheek-piece are preferably finished smooth and true, and when one of its faces has been worn out, the said part may be reversed and used during the useful life of the renewed gears and housing. By the provision of the cheek-piece, when the pump again becomes worn to such extent that it is incapable of performing efficient work, the housing, cheek-piece and gears alone need be removed and renewed, and all of the rest of the pump

mechanism may be continued in service indefinitely.

I attain these objects by the means set forth in the detailed description which follows, and as illustrated by the accompanying drawing, in which—

Figure 1 is a central vertical longitudinal section taken on line 1—1 of Fig. 2, showing a double drive rotary pump, to which my improvement is applied. Fig. 2 is a front end elevation of the same. And Fig. 3 is a side elevation of the cheek-piece, showing the area engaged by the pump gears, which is preferably ground.

In the drawing, the body of the pump comprises two parts, as 3—4, which are connected and spaced by integral lateral webs *a* (see Figs. 1 and 2), and supports all of the working and other parts of the pump. The head 3 comprises parallel twin barrels 3'—3^a, which are bored out axially, as at 3^b, to receive the two driving shafts, as 5—5'. The front end of the head 3 is formed with an oval perforated flange 3^c. The free ends of the barrels 3'—3^a are counter-bored and threaded to receive packing glands 6, and packing 6', to prevent water or other liquid handled by the pump from leakage around the shafts. The tail-piece 4 is formed with barrels 4'—4^a, which register with barrels 3'—3^a, and are bored axially at 4^b, to also journal the shafts 5—5'. The tail-piece 4 may also be provided with an oval flange 4^c, which may be formed with perforated ears 4^d, for attaching the pump to any suitable support. The left end of the shaft 5, according to Fig. 1 of the drawing, is fitted with a spur gear 7, that meshes and drives a similar gear 7', which is rigid to the corresponding end of shaft 5'. Gears 7—7' are formed with similar hubs 7^a, that are operatively disposed in counter-bores 4^e of the barrels 4'—4^a, the hub of gear 7' being preferably journaled in a bushing, as 7^c, that may be rigid to the barrel 4^a. The gear 7 is counter-bored at 7^d, and is also formed with a diametric slot 7^e, to facilitate inserting a power driven shaft, a clutch, or the like (not shown), by which the whole pump mechanism may be operated. Beyond the head 3 is disposed a housing 8, having a

100

perforated flange 8', that coincides with the flange 3^a, and between said flanges is disposed a plane removable and reversible cheek-piece or lining, as 9, that overlies the face 3^a of the head, and being perforated, like said flanges, and all of said parts being detachably secured by screws 8^a. Within the housing 8, are mounted, upon reduced portions 5^a of the shafts, the pumping-gears, as 10—10', which are keyed respectively to the shafts, as at 5^c. The inner ends of gears 10—10' are in normal frictional contact with the ground outer-face 9' of the cheek-piece 9, while their opposite ends have similar contact with the ground inner wall 8^c of the housing, the said wall being formed externally with a contracted boss 8^d having socket bearings 8^e, in which the protruding ends 5^a of the shafts are journaled. The gears 7 are respectively keyed to the shafts 5—5', as shown at 5^d. The hubs 7^a of gears 7—7' are preferably formed with circumferential grooves 7ⁱ in which may be disposed set-screws, as 7^x carried by the barrels 4'—4^a, to prevent longitudinal movement, or escape, of the shafts when the housing 8 and pumping gears 10 are removed.

The water or other fluid to be pumped by the gears 10—10' may enter the housing 8 through a pipe 12, which discharges into a cavity 13, from which the gears carry the fluid to a similar cavity 13', that discharges into a pipe 12'.

By driving the pump gears 10—10' simultaneously by the twin shafts 5—5', which in turn are driven by the gears 7—7', the gears 10 are enabled to operate more freely and orderly and with a minimum of grinding friction and thrust, and practically all undue wear and binding of the teeth common to the single drive pumps, are eliminated. This not only tends to prolong the life of the pumping gears, but greatly reduces the power factor.

Obviously, ball-bearings may be substituted for the packed bearings herein shown, and other changes or modifications may be made without departing from the spirit of the invention.

Having thus described my invention, what I claim, is—

A pump composed of a head having barrels and having an integral outwardly extending flange at one end thereof, shafts in the barrels extending outwardly from said flange, a one-piece cheek piece having one face abutting the outer face of the flange and having openings to receive the shafts and being removable from the shafts by movement of the cheek piece longitudinally of the shafts, pumping gears on the end portions of the shafts, a housing enclosing said gears and having socket bearings to receive the ends of the shafts and further having an outwardly extending flange which abuts the other face of the cheek piece, said flanges of the head

and of the housing and of the cheek piece having registering perforations disposed beyond the housing, fastening means extending through said registering perforations, and means to drive the shafts.

In testimony whereof I affix my signature.

MEAD HEDGLON.
